COMBINED LOCK AND HANDLE UNIT FOR DOORS

Lea S. Schultz, Newport News, Va., assignor to Newport
News Shipbuilding and Dry Dock Company, Newport
News, Va., a corporation of Virginia

Filed Oct. 28, 1960, Ser. No. 62,650

Term of patent 14 years

(Cl. D50—7)

FIG. 1 is a perspective view of a combined lock and handle unit for doors, showing my new design;

FIG. 2 is a front view;

FIG. 3 is a top plan view;

FIG. 4 is a side view, viewing the article from the left as seen in FIG. 3; and

FIG. 5 is a side view looking at the right side of FIG. 3.

I claim:

The ornamental design for a combined lock and handle unit for doors, as shown.
